FIG. 10.

UNITED STATES PATENT OFFICE.

ALLAN PINKERTON, OF NEW YORK, N. Y.

PICTURE-DISPLAYING CABINET.

No. 902,833.

Specification of Letters Patent.

Patented Nov. 3, 1908.

Application filed January 31, 1908. Serial No. 413,541.

To all whom it may concern:

Be it known that I, ALLAN PINKERTON, a citizen of the United States, residing in the borough of Brooklyn, city and State of New York, have invented certain new and useful Improvements in Picture-Displaying Cabinets, of which the following is a specification.

In the modern system of identifying and keeping track of criminals, it has become a general practice to photograph every person charged with a serious crime, and also to take certain other data, such as Bertillon measurements to be preserved for the purpose of making identification sure at a future time. A great many of these photographs naturally accumulate in the course of time, and in large detective bureaus, or at the headquarters of the police departments of the various large cities, is it necessary to have these photographs always ready for convenient inspection.

My present invention relates to a cabinet for holding a number of these photographs in such way that they may be readily inspected, and at the same time protected from the wear incident to repeated handling. My cabinet may also be put to a variety of other uses, such as the display of works of art, postal cards, samples, or any articles of a character adapted to be displayed in a cabinet, and which require protection and careful handling, together with accessibility to inspection.

For the purposes of illustrating my invention, I have chosen one specific form, which is shown in detail in the accompanying drawings, but I do not wish to be limited thereto as it is obvious that many changes may be made in this specific embodiment which will fall within the scope of the claims.

In these drawings Figure 1 represents a vertical section of my improved invention taken along the line I—I of Fig. 8, the cabinet being shown in closed position. Fig. 2 is a similar section taken along line II—II of Fig. 8, the cover of the cabinet being shown raised, and three of the picture holding leaves being turned into upright position. Fig. 3 is a longitudinal section on an enlarged scale of one of the picture holding leaves, parts being broken away. Fig. 4 is a transverse section of the edge portions of two adjacent leaves. Fig. 5 is a detail section on line V—V of Fig. 1. Fig. 6 is a detail section

on line VI—VI of Fig. 1. Fig. 7 is a detail view of a portion of one of the rack members showing the configuration of the notches. Fig. 8 is a top plan view of the cabinet, a portion of the cover thereof being broken away. Fig. 9 is a fragmentary front elevation of the cabinet, the parts being shown in the position of Fig. 2. Fig. 10 is a plan view on an enlarged scale of a portion of one of the picture holding leaves.

Referring to the drawings by reference numerals, 1 is the body or box portion of the cabinet comprising a bottom, two vertical sides of the configuration shown in Figs. 1 and 2, and one vertical end, the other end of the box being open. To the upper edge of the end is hinged at 6 the cover 2, which is formed of two sections 3 and 4 hinged together at 5. The section 3 of the cover is made just long enough to reach to the angle 7 of the box sides, the section 4 extending from this angle to the bottom of the box. This section may be provided at its lower portion with a lock 8 for locking the cover to the box and with handles 9, if desired. The upper edges of the box sides are preferably provided with inturned stepped shelves 10 shown in detail in Fig. 5, which support the cover sections and form lateral guides therefor. The cover sections are preferably provided along their edges at suitable intervals with dowel pins 11, which enter corresponding holes in the shelves 10, and serve to hold the sides and cover together when the cover is closed. When the cover is in raised position, it is supported by a pair of links 12 pivoted to lugs 13 carried by the cover, the free ends of said links being provided with longitudinal slots 14 in which work studs 15 carried by brackets 15^a attached to the box sides. These links preferably have attached thereto plates 16, which cover the slots 14 and the studs presenting a finished appearance and preventing the sides of the slot from spreading. The cover section 3 is preferably provided near the hinge 6 with a transverse rib 17, which serves to strengthen it, and also to provide a support for the picture holding leaves 18 when those leaves are turned into upright position.

For supporting the picture holding leaves 18 within the cabinet, I provide a rack formed of two inclined members 19 and 20, one at each side of the cabinet and attached thereto. These inclined members are pref-

erably supported midway of their length by struts 21. Fig. 6 shows in transverse section the member 20, which is provided with a series of holes 22 for the reception of the pintles 23 of the leaves 18. The member 19 is similar to the member 20, except that in place of the holes 22, slots or notches 24 are provided, which receive the pintles on the other sides of the leaves 18. These slots or notches preferably have substantially vertical walls, the lower wall being curved or hooked over slightly toward the upper wall at its upper end, as shown most clearly in Fig. 7, to prevent the pindle from slipping out too easily.

The picture holding leaves 18 for use in this cabinet may be constructed in a variety of different ways, but I have devised one construction, which I find particularly convenient and serviceable, and which is illustrated in detail in Figs. 3, 4 and 10. The body of this leaf is preferably constructed of a thin sheet of metal 25 stiffened at its lower edge by a transverse wire or rod 26, and at its upper edge by a rod 27, the ends of which project beyond the body of the leaf to form the supporting pintles 23. The side edges of the leaf are stiffened by means of channel members 28, which also serve the purpose of spacing members to hold the leaves apart, and to prevent the pictures 29 attached to one leaf from rubbing against those attached to the next adjacent leaf and becoming injured. The leaves are preferably of sufficient size to hold a considerable number of pictures, those illustrated being designed to hold one hundred photographs, fifty upon each side. These are arranged in five rows, ten in each row. For holding the pictures 29 in these rows, I attach to the leaves transverse strips 30, which are carried by and fixed to rods 31, which in turn are mounted in bearings 32. These bearings 32 are preferably formed of suitable bent or curved over portions of metal strips 33, which are riveted to the leaves. The strips 30 are normally pressed down and made to clamp the photographs by springs 34. I find it most convenient to use a pair of these clamping strips arranged end to end for holding each row of pictures, each strip holding half of a row, and being mounted on its own supporting rod 31. Each rod is provided at its outer end with some means for turning it, such as the thumb piece 35, so as to raise the strip 30 to permit insertion or removal of pictures. These spring pressed clamping strips hold the upper edges of the pictures, the lower edges thereof being retained in place by being slipped under the slightly raised edges 36 of transverse strips riveted to the leaves, which may be the same strips 33, which carry the bearing rods 31 of the spring pressed clamping strips, which hold the upper edges of the next succeeding row of photo-

tographs. For the purpose of spacing the photographs laterally from one another, I preferably strike up from the body of the leaves, portions 37.

It will be seen that the arrangement just described for holding the pictures is duplicated upon the two sides of each leaf, the relative arrangement of the movable and fixed clamping strips being reversed upon the upper and lower sides. As the result of this, the pictures on the two sides will be relatively reversed, and when looking at the pictures on the top of the leaf, they will be erect, and when the leaf is turned into upright position, the pictures on the bottom of the leaf will also be erect.

I preferably construct all the parts of the cabinet of metal, which makes it very durable and prevents its destruction by fire.

I have found a cabinet constructed in accordance with my invention very convenient in use and capable of holding a large number of photographs in comparatively small compass, at the same time permitting all of them to be easily inspected, and permitting the ready removal of any particular picture. It is particularly important to provide for such removal as various data referring to the picture are usually inscribed on the back thereof. It is also possible to remove a whole leaf, if for any reason it becomes desirable, as the leaf may be tilted slightly to raise one of its pintles from the open notch, it then being a simple matter to slip the other pindle out of the hole in the other member of the rack.

Having thus described the preferred embodiment of my invention, I claim

1. In combination a cabinet having an open top, a leaf supporting rack in said cabinet, a series of leaves mounted in said rack, each leaf provided with picture holding means, said means comprising fixed transverse strips slightly raised at one edge, and hinged transverse strips adapted to be pressed against the leaf by springs.

2. In combination a cabinet, a rack therein, a series of sheet metal picture holding leaves pivotally mounted at one end in said rack and stiffening channels attached to each side of the side edges of said leaves, said stiffening channels serving also as means to space the leaves apart.

3. In combination, a cabinet, a series of picture holding leaves, and means in the cabinet for supporting the leaves therein, each leaf being provided on each side thereof with picture holding devices comprising fixed strips having one edge thereof slightly raised, and movable strips, rotatable rods to which said movable strips are fixed, an end of each rod projecting beyond a side of the leaf and being provided with a thumb piece by means of which it may be rotated, and the movable strip attached thereto may

be raised, and springs for pressing down said movable strips.

4. In combination, a cabinet, a series of picture holding leaves and means in the cabinet for supporting the leaves therein, each leaf being formed of sheet metal and being provided with means for holding pictures thereon in rows, and portions struck up from the body of the sheet for spacing the pictures in a row.

5. A picture holding leaf provided with a fixed transverse strip secured thereto, one of its edges being slightly raised to provide a space for the insertion of the edge of a picture, portions of the other edge of the strip being curled to form tubular bearings, a rod journaled in said bearings, a strip fixed

to said rod and a spring tending to hold said last named strip against the leaf.

6. A picture holding leaf formed of a sheet of metal, a stiffening rod at each end of the leaf, the metal being curled about said rods at said ends, the rod at one end projecting at each side of the leaf to form pintles, stiffening members secured along the side edges of said leaf and projecting from the plane thereof to form means for spacing adjacent leaves apart and picture retaining means carried by the leaves.

ALLAN PINKERTON.
